UNITED STATES PATENT OFFICE

JOHN EDWARD THORNTON, OF LONDON, ENGLAND, ASSIGNOR TO JOHN OWDEN
O'BRIEN, OF MANCHESTER, ENGLAND

MULTICOLOR CINEMATOGRAPH AND OTHER FILM

Application filed May 5, 1924, Serial No. 711,254, and in Great Britain May 18, 1923.

This invention relates to the manufacture and production of double width multi-color cinematograph film-positives either in four or three colors, of the screen-filter type, as described in my co-pending application, Serial No. 711,251, filed May 5, 1924, upon one half of which double width film is formed a half-image or section-picture in two colors and upon the other half another half-image in two other colors, both half-pictures being complementary to each other, and both half-pictures being necessary to produce a complete or full picture.

According to this invention, I make a positive film in which the images are produced on a silver bromide panchromatic emulsion by printing from a negative through the celluloid support and the two two-color screens interposed between the celluloid and the emulsion, the film being of double standard width adapted to receive partial images in two colors upon both half widths or strips.

To more clearly illustrate the invention, attention is invited to the accompanying drawings, in which:—

Figure 1 is a plan view of a double width film sensitized with a silver bromide emulsion.

Figure 2 is a transverse section greatly enlarged in depth through a double width film material, the picture being printed through the color screen and the celluloid base as shown by the arrow.

Figures 3, 4, 5 and 6 are plan views greatly enlarged of portions of the color screens adjacent to the center line of the double width film.

Figure 7 is a plan view of a double width film showing a pair of images formed one upon each half, the images having been printed through their respective color screens.

Referring to the drawings, A designates the celluloid support which is made in double width of single thickness and is, therefore, as will presently appear, made to form the two strips $a-a'$. Upon this support is placed an adhesive substratum B, the layer C of the two-color filter screens to each strip $a-a'$ with the final panchromatic emulsion

D being placed and adhesively attached to the support through the medium of the substratum.

This is accomplished in the following manner, viz:—

55

Structure of the negative film

As already stated, it is preferred to print the screen-film positives in the double-width from a pair of screen-film negatives, also of 60 double width.

The method of producing the screen-negatives is fully described in applications Serial Nos. 711,253 and 711,254, both filed May 5, 1924, and the manufacture of the screen-film 65 negative-material is fully described in application Serial No. 711,251, filed May 5, 1924. But briefly the film-material comprises a double-width transparent base or support A of celluloid or other waterproof material to 70 the face of which is applied an adhesive substratum B and superimposed upon the substratum two filter-screens C are formed side-by-side, one of which filters two colors of the subject photographed and the other screen 75 the remaining two colors. Superimposed upon these two screens is a layer of rapid panchromatic emulsion D, the pictures being photographed thereon by exposing the film in the camera with the celluloid at the front, 80 so that light passes first through the celluloid, then through the two filters, and thence to the sensitive layer, upon which two component images are thus formed side by side, both images being differently filtered, but 85 forming a complementary pair capable of producing prints which give a complete color-reconstruction of the original subject.

The screens of the negative consist of a mosaic of fine lines, dots or grains of color, 90 two colors being alternately interspersed on one half the film and two different colors interspersed on the other half and in the manner as shown in Figs. 3, 4 and 5.

For four-color pictures there are four such colors in the pair of screens, but for three color pictures there are only three colors, one of the colors being repeated in both screens so that there are still two colors in each screen.

Structure of the positive film

The film-material for the positive pictures is identical with the negative-material above described, but with the difference that it is 5 only half standard thickness. The screens are made for each four-color or three-color pictures as in the negative film, and composed of a mosaic of fine lines, dots or grains of color, two colors being alternately interspersed on one half the film and two different colors interspersed on the other half.

In the present invention each pair of differential positive images is printed as black 15 silver images of a negative character in one layer of non-colored sensitive silver-bromid emulsion superimposed upon a screen of colored lines, dots, or other pattern which are visible by transmitted light only to the extent 20 allowed by the silver image, which forms a mask or "cut-out" for portions of the color-screens and allows light to pass through the remainder and thus constitute the positive picture.

The positive process used in this invention 25 is therefore quite different from the processes used in any of the other applications in which the images themselves are colored images of a positive character.

For a four-color print the color-screens will 30 be a complementary pair such as crimson red and blue green upon one half of the film, and another complementary pair such as blue-violet and orange-yellow upon the other half.

In this way a quadrate of color is completed. 35 For a three-color print the color-screens upon each half will be only semi-complementary in their coloring, because, as shown in Fig. 6, the first color such as red will be upon one half, the second color such as blue upon 40 the other half, and the third color such as orange-yellow will be repeated upon both halves, being interspersed with the colors already there. In this way the trial of color is 45 completed.

Printing the color positives

The double-width positive material is preferably exposed and printed by projection, 50 either through one large lens which covers the full width of strip and projects both images, or through two lenses which each cover only half the strip, each lens projecting each image separately, which permits of adjustment of 55 lenses to correct any deviation from strict accuracy of registration.

Modifications

60 A number of modifications are possible within the scope of the invention without departing from the principles described. For example:—

The two negatives may be formed upon two 65 separate single-width films, and the two posi-

tives may also be printed upon two separate single-width films.

Four-color and three-color film-negatives and film-positives may be made of the various rectangular forms for ordinary amateur 70 and professional photography. This system gives not only a simpler method of producing color positives but also a better result than most of the color-photograph systems now in use.

What I claim as my invention and desire to protect by Letters Patent is:—

1. A double width multi-color screen-mosaic picture positive comprising a double width film of transparent material, a color-mosaic screen in two colors covering each half width of the double width film, an adhesive substratum between each color-screen and each half width of the film, and a half-picture of negative character upon each half width of the film superimposed on its own color-screen.

2. A double width multi-color screen film picture positive comprising a double-width film of transparent waterproof material, an adhesive substratum covering both halves of said film, a two-color mosaic forming a color screen or light filter entirely covering one half of the double width film and indissolubly attached thereto by the adhesive substratum, a second two-color mosaic forming a color screen or light filter entirely covering the other half of the double width film and indissolubly attached thereto by the adhesive substratum, the two colors of one filter being 100 different from but complementary to those of the other filter, and two half pictures of negative character, one upon each half of the film, each imposed upon its own color screen, the final positive image being actually formed by 105 combination of such portions of the two screens or filters as remain uncovered by the two black silver images of negative character.

3. A double width multi-color screen-film positive as in claim 1; produced with four 110 colors in two images, crimson-red and blue-green on one half of the double width film and blue-violet and orange-yellow on the other half of the double width film.

In testimony whereof I have hereunto set 115 my hand.

JOHN EDWARD THORNTON.
